UNITED STATES PATENT OFFICE.

GLEN M. DYE, OF MINNEAPOLIS, MINNESOTA.

METHOD AND APPARATUS FOR DEVELOPING PRINTS.

Application filed February 9, 1925. Serial No. 7,828.

This invention relates to a method and apparatus for handling photographic prints or negatives and particularly to a machine for developing prints and negatives. In modern print handling establishments it is desirable to have the prints move progressively through the various stages of the operations thereon and it is desirable to have the prints moved and handled as quickly as possible.

It is an object of this invention therefore to provide a simple and efficient developing apparatus comprising a receptacle through which the prints are moved until they are properly developed.

It is also an object of this invention to provide a developing apparatus having means for submerging the prints in the developing liquid, and means for repeatedly engaging and raising the prints in the liquid and again depositing or freeing the same in the liquid.

It is a further object of the invention to provide a method of handling prints which consists in submerging the prints in the developing liquid and repeatedly and successively engaging said prints in the liquid and moving the same through said liquid.

It is a further object of the invention to provide a developing apparatus comprising means for submerging the prints, and means for engaging the prints in the developing liquid, and moving the same through the liquid in said receptacle.

It is a further object of the invention to provide a novel and efficient structure of receptacle for a developing apparatus.

It is another object of this invention to provide a developing apparatus comprising a receptacle adapted to contain the developing liquid, together with means for progressively moving the prints through said receptacle so that the stage of development of the prints and the time they have been in the developer are definitely related to their position in said receptacle.

It is another object of this invention to provide a developing apparatus comprising a receptacle adapted to contain the developing liquid, together with means for progressively moving the prints through said receptacle at a uniform rate of speed.

It is still another object of the invention to provide a developing apparatus comprising a receptacle adapted to contain the de-

veloping liquid, a submerging means for submerging the prints, and means for lifting and moving the prints operated in synchronism with said submerging means whereby there is a minimum of friction on the prints.

These and other objects and advantages of the invention will be fully set forth in the following description made in connection with the accompanying drawings in which like reference characters refer to the same parts throughout the different views, and in which,

Fig. 1 is a view in side elevation of the device;

70

Fig. 2 is a top plan view of the device;

Fig. 3 is a vertical section of a portion of the device taken on the line 3—3 of Fig. 2, as indicated by the arrows;

Fig. 4 is a vertical section of the device taken on the line 4—4 of Fig. 3, as indicated by the arrows; and

Fig. 5 is a vertical section taken on the line 5—5 of Fig. 4, as indicated by the arrows, Figs. 4 and 5 being shown on an enlarged scale.

Referring to the drawings, the apparatus comprises a frame having four vertical posts 6 connected at the top by suitable cross pieces 7 having a plate or board 8 extending therebetween adjacent their bottoms and a top plate or board 9 at their upper end. Supported upon the top plate 9 is a receptacle 10. While this receptacle might have various shapes, in the embodiment of the invention shown, it is illustrated as of elongated rectangular shape and the same has spaced upstanding narrow members or ribs 10^a extending above the bottom thereof and in the embodiment of the invention illustrated, the ribs 10^a are shown as integral with the bottom of the receptacle.

Shafts 11 and 12 extend across receptacle 10 adjacent its respective ends and adjacent the top thereof, said shafts being journaled in the sides of said receptacle. As shown in Figs. 2 and 4, the shafts 11 and 12 are offset inwardly of the tank to form crank shafts and depending members 13 and 14 are bent into hook shape at their upper ends and are suspended on said crank shafts, the members preferably being in the form of plates. The members 13 and 14 have secured thereto adjacent the lower end a plu-

rality of spaced rods 15 spaced similarly to the ribs 10^a and being disposed respectively between said ribs. The plates 13 and 14 are provided with holes 13^a, 14^a, respectively, to lessen the resistance to the motion of said plates through the liquid and to prevent surging of said liquid. A bar 16 extends across the receptacle 10 somewhat adjacent one end thereof and carries trunnions journaled in the sides of said receptacle and said bar has projecting therefrom toward said end of the receptacle a plurality of spaced rods 17 which extend forwardly a short distance from said bar in a horizontal direction, are then bent downwardly toward the bottom of receptacle 10, then extend forwardly substantially horizontally having a downward offset adjacent the end of said latter horizontal portion and then extend vertically above the top of receptacle 10, as shown in Fig. 3. At each side of the rod 17 the bar 16 carries a rod 18 which projects forwardly and rests upon a grooved multilated pulley 19, the pulley 19 being secured upon the crank portion of shaft 12 inside of the receptacle 10. The pulleys 19 have a flat side 19^a, as clearly shown in Fig. 5. The shafts 11 and 12 extend across the top of plate 9 and are journaled in bearings 20 secured at one edge of said plate and said shafts have secured thereto outwardly of said bearings, sprockets 21. Each sprocket 21 is connected by a chain 22 to a sprocket 23 secured upon shaft 24 journaled in bearings on the posts 6, which shafts also carry at their outer ends sprockets 25. A chain 26 runs over both of sprockets 25 and over a sprocket 27 carried on a shaft 28 journaled in one of the posts 6, which shaft 40 also has secured thereto inwardly of said post a grooved pulley 29. The pulley 29 is driven by a belt 30 running over a pulley secured to the armature shaft of a motor 31 secured to the plate 8, which motor is illustrated as of the electrical type.

The top plate 9 also has secured thereto an elongated or oblong receptacle 32 having semi-circular end portions. The receptacle 10 also has secured thereto a chute 33, said chute being directed downwardly into said tank in front of the vertical portions of rods 17.

In operation, the developing liquid will be placed in the receptacle 10 substantially at the height indicated by the dotted lines 34. The prints, after leaving the printing machine, will be delivered to the chute 33 and will slide down the same in front of the rods 17, as indicated by the print 35 shown in dotted lines in Fig. 5. The motor 31 will be in operation and motion will be transmitted to the shafts 11 and 12 through the chains and sprockets described so that said shafts are driven in a counter-clockwise direction, as indicated by the arrow in Fig. 5.

Owing to the crank formation of shafts 11 and 12, the plates 13 and 14 will be moved in a circular path at their upper ends and thus the rods 15 will also be moved substantially in a circular path. The motion of the rods 15, it will be noted, will be upwardly when they are substantially at the right hand end of their path of movement, as seen in Figs. 1, 2 and 3, and said rods will move toward the left hand end of receptacle 10 when they are in their upper position and will hence move downwardly when they are substantially at the limit of their movement to the left and said rods will move to the right when they are substantially in their lowest position in the liquid and substantially between the ribs 10^a. The rods 17 will be oscillated vertically about the trunnions of bar 16 so that the right hand end of said rods move substantially vertically. The rods 17, however, will not be moved uniformly with the crank shafts 11 and 12 but as the crank shaft moves the rods 15 downwardly the flat side 19^a of the pulleys 19 will cause the rods 18 to accelerate in their downward movement or move downwardly relatively to the rods 15 so that both rods 17 and 15 move downwardly together, the rods 17 moving relatively to the rods 15. The rods 17, with members 16 and 18, form a submerger or a ducker for the prints as the prints slide downwardly into the developing liquid and are supported by the rods 15 which form the print supporting and traversing means. The print, therefore, as it slides down the chute 33, is repeatedly and successively engaged by the rods 17 and pushed under the surface of the liquid or submerged therein. As the rods 17 rise the rods 15 also rise and move toward the left hand end of the receptacle, as seen in Figs. 1 to 3. The print is thus moved a slight distance toward the left hand end of the receptacle with each movement of the rods 15 about their closed path of movement. The print, of course, is soon completely submerged and passes out of the range of contact with rods 17 and continues its travel lengthwise of the receptacle on the rods 15, said print being repeatedly engaged and raised by said rods, moved a short distance toward the left hand end of the receptacle in said liquid, and again deposited or freed in the liquid. Owing to the described synchronism of movement of rods 15 and 17, there is a minimum of rubbing movement or friction on the surface of the print, the rods 17 being elevated out of contact with the print as the rods 15 move the same to the left. The operator is seated at the side of the apparatus adjacent the receptacle 10 and it may be stated that the receptacle 32 usually carries a developer arresting solution known in the trade as a "short stop." The operator watches the

prints as they are developed in their travel through the receptacle 10. If the print darkens while still under the submerger comprising rods 17, the print is discarded and the same is made over, the time of exposure being varied. If the print darkens after leaving the submerger it can be saved and the operator picks it out of the developing solution and places it in the stop solution in receptacle 32. The narrow members 10* are provided so that the print can be easily picked from the solution. The print cannot sink so that it lies flat against a flat bottom but is always supported in an elevated position above the bottom of receptacle 10 so that the edge is in an convenient position to be engaged by the fingers. It is only necessary, therefore, to make one attempt or one grab, so to speak, for the print in order to pick the same up and transfer it to receptacle 32. If the print is not darkened sufficiently by the time it reaches the end of receptacle 10 it is also made over, the time of exposure being varied. The rate of travel of the print is so determined that the print reaches the left end of receptacle 10 at the maximum time that it is possible to allow the same to remain in the developer. The machine, as at present used in a commercial print developing establishment, is timed for the print to travel to the end of the receptacle in one minute. The operator therefore rely watches the prints as they travel through the receptacle 10 and picks the same of said receptacle when they have reached the requisite degree of darkness, transfers them to the receptacle 32. The prints, of course, will travel farther in receptacle 10 than others before being picked out. It will be noted that the time a print has been in the developing liquid, hence, its stage of development is definitely related to and indicated by its position in the receptacle. As above stated, the apertures 13 and 14 are provided with apertures so that they will cause less motion of the developing liquid as they move therethrough.

From the above description it will be seen that applicant has provided a simple and efficient method and apparatus for developing prints. The prints are automatically referred to the developing apparatus, automatically submerged and moved along in the developer. The prints are only touched by the operator when the same are lifted out of the apparatus and the apparatus is so constructed that the prints will be easily engaged and lifted therefrom. The repeated dipping of the prints and the deposit thereof in the liquid causes a positive and efficient development thereof. The machine is quite simple in construction and entails very little work by the operator. The machine has

been amply demonstrated in actual practice and found to be very successful and efficient.

It will, of course, be understood that various changes may be made in the form, details, arrangement and proportion of the parts of the apparatus and in the steps and sequence of steps of the method without departing from the scope of applicant's invention, which, generally stated, consists in a method and apparatus capable of carrying out the objects above set forth and in the novel steps and arrangement of steps and in the novel parts and combinations of parts disclosed and defined in the appended claims.

What is claimed is:

1. A developing apparatus having in combination, a receptacle adapted to contain developing liquid, means for submerging prints in said liquid, and means for repeatedly engaging the submerged prints in the liquid, lifting the same and again depositing the same in the liquid.

2. The method of handling photographic prints which consists in submerging the exposed prints face upward in a print-treating liquid in a receptacle and repeatedly at substantially regular intervals engaging the prints in the liquid and lifting the same and again depositing the same in the liquid while maintaining said prints in horizontal position.

3. A print-treating apparatus having in combination, a receptacle adapted to contain a print-treating liquid, movable means for submerging the prints in the liquid in said receptacle, and means in said receptacle for engaging said prints in said liquid, lifting said prints and moving the same longitudinally of the receptacle.

4. The method of handling photographic prints which consists in submerging the exposed prints in a developing liquid contained in a receptacle, and successively engaging and lifting said prints in said liquid and substantially simultaneously traversing the same in said receptacle.

5. The method of handling photographic prints which consists in submerging said prints face upward in a print-treating liquid, engaging said prints on the underside and intermittently progressing the same at regular intervals in said liquid and moving the same vertically substantially between the progressions thereof.

6. A print-treating apparatus having in combination, a receptacle adapted to contain the developing liquid, and means for engaging said prints in said liquid on the underside and moving the same therethrough longitudinally of said receptacle.

7. A print-treating apparatus having in combination, a receptacle adapted to contain a developing liquid, submerging means at one end of said receptacle for submerging

posed prints, and movable means in receptacle for repeatedly and successively lifting the prints in said liquid, moving same longitudinally of the receptacle and again freeing the prints in said

print-treating apparatus having in combination, a receptacle adapted to contain developing liquid, movable means adjacent to the receptacle for submerging the prints with their emulsion sides uppermost, for delivering the prints to said receptacle and submerging means, and means for receptacle for engaging said prints beneath and progressively moving the prints longitudinally thereof.

print-treating apparatus having in combination, a receptacle adapted to contain developing liquid in which said prints are disposed, and a conveyor disposed beneath said prints movable in said receptacle progressively moving said prints through said receptacle longitudinally of said receptacle.

A print-treating apparatus having in combination, a receptacle adapted to contain developing liquid, print engaging means in said liquid, and means for operating said means to cause the same intermittently to engage said prints from beneath above said prints through said liquid longitudinally of said receptacle.

A print-treating apparatus having in combination, a receptacle adapted to contain developing liquid, means at one end of said receptacle for submerging the prints, conveyor extending longitudinally of said receptacle for repeatedly lifting the prints, and advancing the same longitudinally of said receptacle.

A print-treating apparatus having in combination, a receptacle adapted to contain developing liquid, print supporting means in said receptacle, said means having a means of movement in said receptacle including a movement in one direction substantially longitudinally of said receptacle in said liquid, then a movement substantially upwardly toward the top of said receptacle, a movement substantially longitudinally of said receptacle in the reverse direction and then a movement substantially downwardly in said liquid, and a vertically oscillating submerging means movable substantially to submerge the prints in said liquid while said supporting means is moved substantially downwardly and disposed said supporting means when the same are moving longitudinally of said receptacle by there is substantially no rubbing of the prints.

A print-treating apparatus having in combination, a receptacle adapted to contain developing liquid, a print supporting conveyor in said receptacle comprising rods extending longitudinally of said

receptacle and movable in closed paths in vertical planes for engaging and advancing the prints in said receptacle.

14. A print-treating apparatus having in combination, a frame, a receptacle adapted to contain a developing liquid, means for submerging prints in said liquid, means for advancing prints in said receptacle, a second receptacle on said frame adjacent said first mentioned receptacle adapted to contain a developer arresting solution, and means on said frame for operating said first two mentioned means.

15. A print-treating apparatus having in combination, a receptacle adapted to contain a developing liquid, a conveyor comprising spaced rods extending longitudinally of said receptacle for supporting prints, means for moving said rods in closed paths and lifting the prints, advancing the same and depositing said prints in the liquid, and a submerger adjacent one end of said conveyor comprising vertically reciprocating spaced rods.

16. A print-treating apparatus having in combination, a receptacle adapted to contain a developing liquid, means for submerging prints in said liquid, a print supporting means co-operating with said submerging means for progressively advancing the prints in said receptacle, and an operating means for said submerging means and print supporting means for operating the same in synchronism.

17. A print-treating apparatus having in combination, a receptacle adapted to contain a developing liquid, crank shafts traversing said receptacle adjacent the ends thereof, members pivotally supported on said crank shaft and depending into said receptacle, a plurality of spaced rods secured to said members adjacent the bottom of the receptacle and extending longitudinally thereof, a member extending transversely of said receptacle adjacent one end mounted for oscillation about an axis extending transversely of said receptacle, a series of spaced rods secured to said last mentioned member extending longitudinally of said receptacle and downwardly thereinto, and means carried by said cranks for vertically reciprocating said last mentioned rods whereby all of said rods are synchronously operated.

18. A print-treating apparatus comprising a receptacle adapted to contain a developing liquid having spaced narrow members extending above the bottom thereof and longitudinally thereof.

19. A print-treating apparatus comprising a receptacle adapted to contain a developing liquid, said receptacle having a plurality of spaced narrow ribs projecting upwardly from the bottom thereof and extending longitudinally of said receptacle.

20. A print-treating apparatus having in

- combination, a receptacle adapted to contain the developing liquid, spaced narrow members extending longitudinally of said receptacle above the bottom thereof, and a 5 print supporting conveyor in said receptacle comprising a plurality of spaced rods extending longitudinally of said receptacle and disposed respectively between said narrow members.
- 10 21. A print-treating apparatus having in combination, a receptacle adapted to contain print-treating liquid in which said prints are disposed in substantially flat condition, and means movable upwardly from beneath 15 said prints for engaging the same and moving them longitudinally of said receptacle.
22. A print-treating apparatus having in combination, a receptacle adapted to contain print-treating liquid in which said prints 20 are disposed in substantially flat condition, spaced means for supporting said prints, and means disposed between said means for engaging said prints from beneath and moving the same longitudinally of said receptacle.
23. A print-treating apparatus having in combination, a receptacle adapted to contain print-treating liquid in which said prints are disposed in substantially flat condition, 25 and means extending longitudinally of said receptacle for repeatedly lifting said prints and traversing the same in said receptacle.
24. A print-treating apparatus having in combination, a receptacle adapted to contain print-treating liquid in which prints are 30 disposed, and means for repeatedly engaging the submerged prints in the liquid, lift the same and again depositing them in liquid.
25. A print-treating apparatus having in combination, a receptacle adapted to contain print-treating liquid in which prints are disposed, and means for repeatedly engaging the submerged prints in the liquid, lift the same, traversing the same in the receptacle, and again depositing the same in liquid.
26. A print developing apparatus having in combination, a receptacle adapted to contain developing liquid in which the prints are disposed, face upward, and means beneath said prints for moving the same 35 forwardly through said liquid whereby the stage of development of a print will be indicated by its position in said receptacle.
27. The method of developing photographic prints which consists in placing the prints face upward in a receptacle containing developing liquid engaging said prints from beneath and progressively moving the same in said receptacle whereby the degree of development of said prints is indicated by their positions in said receptacle.
- In testimony whereof I affix my signature:

GLEN M. DY
